UNITED STATES PATENT OFFICE.

LAWRENCE GRUENENFELDER, OF PIERRON, ILLINOIS.

METALLIC RAILWAY-TIE.

1,083,487.

Specification of Letters Patent.

Patented Jan. 6, 1914.

Application filed May 26, 1913. Serial No. 770,018.

To all whom it may concern:

Be it known that I, LAWRENCE GRUENENFELDER, a citizen of the United States, residing at Pierron, in the county of Bond, State 5 of Illinois, have invented certain new and useful Improvements in Metallic Railway-Ties; and I do hereby declare the following to be a full, clear, and exact description of the invention, such as will enable others 10 skilled in the art to which it appertains to make and use the same.

The present invention is directed to improvements in metallic railway ties, and has for its object to provide a device of this 15 character, which is exceedingly simple in construction, and one which can be manufactured at a minimum cost.

A further object of the invention is to provide a metallic railway tie with novel 20 means for securing the rails thereto.

With these and other objects in view, this invention resides in the novel features of construction, formation, combination and arrangement of parts to be hereinafter more 25 fully described, claimed and illustrated in the accompanying drawing, in which:—

Figure 1 is a side elevation of the device. Fig. 2 is a top plan view of the same. Fig. 3 is a sectional view on line 3—3 of Fig. 2. 30 Fig. 4 is a similar view on line 4—4 of Fig. 2.

Referring to the drawing, the numeral 1 designates the tie which has a flanged base 2, the upper surfaces of which are beveled, 35 as at 3. Formed integral with the central portion of the base 2 is a vertical web 4, the upper edge of which terminates in a head 5, the sides of which overhang the sides of the web 4. Formed adjacent each end of the 40 head 5 is a recess 6, the base of which is

provided with spaced grooves 7, which result in the treads 8, and upon which the flanged base of the rail 9 rests, while the lower edges of the fish plates 10 engage the grooves 7. The head 5 has formed at its 45 outer ends the thickened portions 11, the purpose of which will appear later.

The fish plates 10 are provided with notches 12, which are adapted to register with the openings 13, which extend through 50 the head 5 and thickened portions 11, so that when the usual spikes 14 are engaged in the notches and openings the lower ends thereof may be bent into engagement with the lower edges of the thickened portions 11, 55 thereby effectually fastening the rails and fish plates to the tie.

What is claimed is:—

A metallic railway tie comprising a base, 60 a web formed integral therewith and having a head formed upon its upper edge, thickened portions formed at the ends of the head, recesses formed adjacent the ends of the head, the bases of which being provided with transverse grooves, treads formed in 65 the recesses for supporting the flanged base of the rails, fish plates engaging the rails and having their lower edges engaging said grooves, spikes engaging the fish plates and passing through the head and thickened 70 portions, said spikes having their lower ends bent into engagement with the lower edges of the thickened portions.

In testimony whereof, I affix my signature, in the presence of two witnesses.

LAWRENCE GRUENENFELDER.
